ABSTRACT OF THE DISCLOSURE

A device controlling the automatic cutoff of a single-journey section, containing a magnetic deposit, from an inserted ticket comprises three parallel ferromagnetic cores, each having a winding, which are arranged at the three corners of an equilateral triangle. When the ticket is in its check position, its deposit affects the coupling between two cores. The windings of one of these and of the third core are so fed from a common A.C. source that, in the absence of a ticket deposit the voltage induced in the winding of the remaining core supplemented if desired by a supplement voltage derived from the same A.C. source constitutes a small bias voltage in antiphase to the output voltage produced by a magnetic deposit, and the resultant biased output is rectified and compared with a reference voltage, also derived from the same A.C. source and rectified to produce a D.C. output of one polarity in the presence of a magnetic deposit between given limits of magnetic conductance and of the opposite polarity in all other cases. This D.C. comparator output is utilized to operate a guillotine and printer via a trigger circuit and a logic circuit, the latter controlled by a front microswitch opened by the presence of a ticket and a rear microswitch opened by abutment of the ticket against the stop, to prevent operation of the guillotine and printer until the ticket rests against the stop and to prevent reoperation until the front microswitch has been cleared.

DISCLOSURE

This invention relates to apparatus for this detection of a magnetic or conductive deposit on a carrier and is more particularly intended for, though not exclusively applicable to, machines for checking tickets having a magnetic imprint and more particularly for the checking and automatic part-cancellation of magnetic (or if desired electro-conductive) imprints arranged in a uniformly spaced series from one end of a ticket form towards the other, each imprint representing a journey, fare stage, or the like.

According to the present invention the device includes means for locating the carrier with the deposit in a predetermined position, and a magnetic bridge in which three magnetic cores, each having a winding, are magnetically coupled by their fluxes and so arranged with reference to the deposit when the carrier is in said predetermined position, that this deposit discriminatively influences the flux that couples one of the cores with one of the other two cores, means for feeding the winding of one of the cores with alternating current, preferably of radio-frequency, to form a transformer primary winding, while the winding of a second core is utilised as a secondary winding, the winding on the third core being connected in series with either of the two windings referred to in such manner as to oppose the effect of the same, thus in the case of series connection with the primary winding, producing in the secondary winding a flux which is opposite and approximately equal to the flux produced by the said primary winding, or in the case of series connection with

2

the secondary winding, to produce, as a result of the flux passing through the third core from the primary winding, a voltage which is opposite and approximately equal to the voltage produced in the said secondary winding. It will be appreciated that with this arrangement a secondary-voltage output is obtained which, from a predetermined low value occurring in the absence of any deposit, will, in the case of a magnetic deposit, be either substantially in phase or substantially in antiphase with the source, according to the direction of the residual unbalance, and will increase in one direction, for example in a positive direction relating to the in-phase voltage, in accordance with the amount of the deposit, while the presence of an electroconductive nonmagnetic deposit will produce a variation opposite to the first-mentioned variation, i.e., in the example a variation in antiphase to the input voltage. It will also be appreciated that the magnitude of the variation will depend on the permeability or electroconduction qualities of the deposit.

Preferably the arrangement is such that in the absence of a deposit there is a residual secondary voltage in antiphase to the variation produced by the presence of a magnetic deposit. In this case a magnetic deposit of a permeability value not exceeding a predetermined value will reduce the absolute value of the output voltage, since the variation produced is in phase opposition to the residual voltage mentioned. For very small permeability values the resultant output will thus be of the same phase as the residual output but of smaller value, and for somewhat greater permeability values the resultant output will pass through zero and with increasing permeability a resultant voltage will appear which is in phase opposition to the residual voltage, but up to the predetermined value of permeability is still smaller in value than the residual voltage (or a desired fraction thereof); when however the permeability is above the permitted value, the resultant output voltage will rise to a value (in phase opposition to the residual voltage) which is greater than the residual voltage. A conductive deposit will produce variation in phase with the residual voltage and will therefore always produce a resultant voltage output higher than the residual voltage. Thus, if the absolute value of the output voltage is utilised to produce an acceptance response if the residual voltage is reduced below a predetermined limit, and a rejection response or no response if the residual voltage is left unaltered, or reduced less than to the predetermined limit, a device has been achieved which will accept only deposits of magnetic material within predetermined magnetic-conduction limits.

Preferably the magnetic bridge comprises three cores extending parallel to each other at the corners of an equilateral triangle and embedded with their windings in a molding of insulating material. According to a further preferred feature of the invention, the magnetic bridge is fed from an oscillator, and the voltage output of the bridge in the absence of a deposit is arranged, either by the construction of the bridge, or by superposition of a suitable voltage derived from the same oscillator, to be in antiphase with the voltage variation produced by the presence of the acceptable deposit, and this output as well as a reference voltage also derived from the same oscillator are each rectified, the rectified voltages being supplied to a comparator which produces a D.C. output of one given polarity when the voltage of the biased bridge output is greater, and of the opposite polarity when the biased bridge output is smaller than the reference voltage. The output of the comparator is then fed to a trigger or gate circuit which becomes operative to produce an acceptance response only in the latter case and subject further to a logic circuit which has two other inputs respectively controlled by two microswitch feelers each controlled by the presence of a ticket in the device, one feeler being arranged to

be operated only when a ticket is fully inserted against a stop determining the checking position, and the other being arranged at a point on the path of the ticket from an insertion opening to the stop so as to be operated whenever a ticket has been inserted beyond an intermediate point of this path. The logic circuit is arranged to permit an acceptance response only when both microswitches have been operated, and then to prevent a further acceptance response until both, or at least the last-mentioned one, of the microswitches has been closed and reopened after the preceding acceptance response. In the preferred embodiment the response consists in the issue of a pulse which is utilized for initiating the operation of a mechanical device including a guillotine which cuts off an end portion of the ticket including the deposit nearest to this end, the length of such portion being equal to the spacing of the individual deposits; preferably the acceptance pulse also causes a printing device to print identification marks on the opposite face of the remainder of the ticket, near the end of this remainder.

It will be readily appreciated that the provision of the logic circuit not only ensures that the mechanism is not operated until the ticket has reached the appropriate position in which the first remaining deposit is in the correct position, and that the guillotine cut will be so positioned that the remainder of the ticket will be operative at the next insertion if any deposit is left, but that the logic circuit also prevents accidental cutting off of more than one deposit at a time due to the user's maintaining pressure on the ticket after the first operation of the guillotine.

One embodiment of the invention as applied to such ticket checking machines will now be described in more detail with reference to the accompanying drawings, in which:

FIGURE 1 is a schematic block diagram of the circuit employed.

FIGURE 2 is a schematic perspective view of the magnetic bridge constituting the sensing element.

FIGURE 3 is an enlarged perspective view of a practical embodiment of a sensing element including the magnetic bridge.

FIGURE 4 is a diagram of a suitable rectifier and comparator arrangement.

FIGURE 5 shows a half-wave voltage doubler and rectifier circuit, of which two are combined in the circuit of FIGURE 4.

FIGURE 6 is a circuit diagram of the trigger circuit for response to negative voltage output from the comparator.

FIGURE 7 is a similar trigger circuit suitable for alternative use when response to positive output signals is required.

FIGURE 8 is a circuit diagram of a suitable transistorized oscillator circuit.

FIGURE 9 is a diagram indicating the output of the comparator circuit plotted over the magnetic (positive) or electric (negative) conduction qualities of the deposit under test, assuming a .05-volt response overlap in the trigger circuit between the "on" and "off" states, and

FIGURE 10 is a circuit diagram of a logic circuit which serves to apply the acceptance response of the trigger circuit of FIGURE 6 to a guillotine and printing mechanism when a ticket has been fully inserted into the machine, and then to prevent reoperation of the mechanism until the ticket has been withdrawn.

Referring now first to FIGURE 1, the device according to the invention will be considered as applied to an automatic imprint checking and cancelling machine for tickets having imprints of a magnetic deposit, each representing a journey or part-journey, arranged at one end of the ticket, in uniformly spaced succession from that end. The device comprises an oscillator for a radio-frequency of approximately 1.6 megacycles/sec. which produces three output voltages in phase with each other and has therefore been represented as three generators 1, 2 and 3, driven by a common shaft 4. The output voltage of gen-

erator 1 feeds two series-connected primary windings 11 and 12 of a sensing element 5 which in addition includes a secondary winding 13. The three windings 11, 12 and 13 are respectively wound on cores 14, 15 and 16 which, as shown in FIGURES 2 and 3, extend parallel to each other and are arranged, at the corners of an equilateral triangle 17, in an insulating body 18 encased in a brass sleeve 19. Means 22 are provided for guiding a ticket 10 to, and locating it in, the position shown in FIGURE 3, in which the magnetic imprint 6 nearest to the end of a valid ticket forms a magnetic shunt reducing the magnetic reluctance of the flux path coupling cores 14 and 16, while the magnetic reluctance of the paths coupling core 15 with either of the two cores 14 and 16 is left substantially unaltered. The two primary windings 11 and 12 are so arranged on the cores 14 and 15 that the fluxes respectively produced by them in core 16 due to magnetic coupling are opposite and, in the absence of a deposit-carrying ticket, substantially equal.

Referring now once more to FIGURE 1, the secondary winding 13 is connected in series with a voltage RV_1 , derived from generator 2 by a voltage divider 7, which is in antiphase to such voltage as is induced in winding 13 by the primary windings 11 and 12 in the presence of a ticket having a magnetic deposit in the appropriate position. The resultant composite voltage A will, therefore, in absence of a ticket, be in such "antiphase" position and be equal to the value RV_1 . When a ticket having a magnetizable deposit is in position, the value of this composite antiphase voltage will decrease with increasing amounts of deposit to become zero at a predetermined amount of deposit, and with further increasing amounts of deposit the composite voltage will change to the "in-phase" position and progressively increase in value as the amount of deposit increases. When on the other hand a ticket carrying an electroconductive nonmagnetic deposit is presented, the "antiphase" voltage derived from the winding 13 is added to the "antiphase" voltage RV_1 , and an increased "antiphase" output will appear at A. The said resultant composite voltage A is supplied via an amplifier 8 and a rectifier 9a to one input of a comparator 9 to a second input of which the voltage output o of the generator 3 is supplied via a second rectifier 9b the voltage RV_1 being adjusted to be equal in value to this voltage output o. It will be readily appreciated that with this arrangement in the absence of a deposit-carrying ticket the two input voltages of the comparator 9 are equal, resulting in zero output, and that in the presence of a ticket having an electroconductive deposit the rectified input voltage A will exceed the rectified voltage o, a condition which will produce a positive D.C. output of the comparator 9. Similarly a ticket having a magnetic deposit exceeding a certain amount will produce an in-phase resultant output of greater absolute value than the bias voltage RV_1 , and will thus likewise produce a positive comparator output. On the other hand a magnetic deposit of less than this amount will result in lowering the value of the voltage A below the value of voltage o and will thus produce a negative comparator output. This negative output is utilized to produce, via a logic system 23, an acceptance response when this negative output exceeds a predetermined minimum value sufficient to operate a trigger 22 while ensuring a rejection of magnetic deposits below a predetermined minimum amount as well as of magnetic deposits exceeding a predetermined maximum amount somewhat lower than the above-mentioned certain amount.

The combined rectifier and comparator circuit is shown in FIGURE 4. The amplified output of the sensing element, constituting the first input of the circuit, is represented by a generator 20 producing an A.C. voltage V_1 , while the second input is represented by a generator 3 producing an A.C. voltage V_2 . The circuit of FIGURE 4 can be considered as a combination of two half-wave voltage-doubler rectifier circuits, each as shown in FIGURE 5, to which the outputs of generators 20 and 3 are

respectively supplied, and whose outputs are connected in opposition by a cross-connection 21. It will be observed that since each of the voltages from sources 20 and 3 is rectified individually, and the rectified output voltages are connected in opposition, the comparator and subsequent parts of the circuit are not phase-sensitive but only responsive to the absolute values of the two voltages V_1 and V_2 , and that the output voltages of the comparator will be positive when the voltage V_1 of source 20, that is to say the amplified vector sum of the output from sensing element 11, 12, 13 and the bias voltage from divider 7 is greater than the reference voltage from source 3, and negative in the converse case.

In FIGURE 9 the resultant output voltage of the comparator has been plotted as a function of the presence of magnetic coating material to the right of the zero line and of the presence of electroconductive coating material to the left of the zero line. The figure shows that the comparator will produce no output in the absence of any coating and a negative output in the presence of a moderate amount of magnetic coating, while with progressively greater amounts of magnetic coating the negative output first drops to zero and is eventually replaced by a positive output, which is also present in the case of any electrically conducting nonmagnetic coating material.

The comparator output is fed to a trigger circuit as indicated at 22, FIGURE 1. A suitable trigger circuit using a p-n-p silicon transistor VT_1 in the first stage and n-p-n germanium transistors VT_2 and VT_3 in the second and third stages is shown in FIGURE 6, while FIGURE 7 illustrates an alternative trigger circuit which is intended for use when response to positive, instead of negative output signals is required, and in which the first-stage transistor VT_1' is an n-p-n silicon transistor and the second-stage and third-stage transistors VT_2' and VT_3' are p-n-p germanium transistors. In each case the values of resistors R_1 , R_2 and R_4 are so chosen that $R_1 > R_2 > R_4$, and the current in resistor R_4 , or if desired the voltage drop across R_4 , or part of this voltage drop, can be utilized as output of the circuit.

In the embodiment illustrated in FIGURE 1, a logic control circuit 23 is interposed between this trigger output and the mechanism which serves to cutoff the first available deposit on the ticket and to provide the ticket with an imprint. A suitable logic circuit is illustrated in FIGURE 10. This logic circuit comprises a first microswitch M_1 which is interposed between resistor R_4 of the trigger circuit and the positive terminal marked $+V_e$, and which is so arranged as to be normally closed but to be opened by a ticket when upon full insertion into the machine the ticket strikes an insertion-terminating stop, and a further microswitch M_2 which is arranged to remain closed until the ticket passes an intermediate point of its insertion into the machine. For easier distinction the microswitch M_1 will be referred to as the rear microswitch and microswitch M_2 as the front microswitch. The illustrated logic circuit may be said to comprise a trigger circuit constituted by two transistors J_7 and J_8 which is utilized as a memory device and is arranged to have a wide voltage differential of, for example, 2.0 volt. The first-stage transistor J_7 is biased by a potential divider constituted by two resistors R_{23} and R_{24} connected across a fixed voltage of, for example, 16 volt, to bias the transistor J_7 to the midpoint of the trigger-circuit characteristic, so that the bias voltage is adequate to hold transistor J_7 in its switched-on condition after it has been switched on by the application of an additional voltage, but insufficient to overcome the voltage which is developed at the emitter of transistor J_7 across a resistor R_{27} when the second transistor J_8 conducts. C_{13} is an electrolytic capacitor of high capacitance, for example 2 μ f. The circuit is illustrated in the condition occurring when no ticket is in the machine, and both microswitch M_1 and M_2 are accordingly closed. In this condition the front microswitch M_2 shunts by a low-value resistor R_{25} the

bias that is fed to transistor J_7 thereby rendering transistor J_7 nonconducting and causing transistor J_8 to conduct. At the same time the rear microswitch M_1 connects one end of resistor R_4 to the positive line, causing any output current which may be coming from the preceding trigger circuit via transistors VT_3 , to bypass the logic circuit. On the other hand, a blocking diode D_7 prevents the closing of microswitch M_1 from affecting the bias voltage for transistor J_7 developed across resistor R_{24} . Accordingly transistor J is "off" and transistor J_8 is "on" (conducting) when no ticket is in the machine.

When a ticket is now inserted, it will first open the front microswitch M_2 , thereby allowing the bias voltage developed across resistor R_{24} to rise to its normal level, since the still closed rear microswitch M_1 is prevented by the blocking diode D_7 from short-circuiting this resistor. Since, however, the bias voltage, as explained above, is insufficient in itself to overcome the emitter voltage of transistor J_7 when transistor J_8 conducts, the transistor J_7 remains nonconductive. The ticket then proceeds to its checking position, where its validity is determined by the sensing system. Since the presence of a valid deposit is intended to operate a guillotine cutting the end portion of a ticket, it is important to prevent this operation from taking place until the ticket rests against a stop exactly determining the desired position. To ensure this the rear microswitch M_1 has been provided, which remains closed to prevent an output from the logic circuit from affecting the transistor J_7 until, on reaching the stop, the ticket opens this rear microswitch. In addition the rear microswitch M_1 is utilized to supply, when open, current to a terminal H . This current produces a warning signal when at the time the microswitch M_1 is open due to the presence of a ticket or other object, the output of the trigger transistor VT_3 is a rejection response, while as will be explained below, in the case of an acceptance response microswitch M_1 is reset within a few microseconds to its closed position due to the guillotine operation, thus preventing the appearance of the warning signal.

When a valid ticket has been inserted so that an acceptance response is obtained from the transistor VT_3 , the output current from transistor VT_3 is caused to bypass the base of transistor J_7 via the closed rear microswitch M_1 until the ticket when it is fully inserted, opens the switch, thus allowing the trigger output current to act on the base of transistor J_7 which, when switch M_2 is open, is biased in the conducting direction. The flow of current from transistor VT_3 through resistor 24 will increase the voltage drop in resistor R_{24} sufficiently to switch on transistor J_7 , and as a consequence to switch off transistor J_8 . The switching-off of transistor J_8 is utilized in a manner to be described below, to operate a guillotine and printing mechanism to cut off an end portion of the ticket and apply an imprint to the main portion of the ticket. At the same time the cessation of the current through transistor J_8 and the resistor 29 of relatively low value compared to resistor 28, considerably reduces the voltage drop in resistor R_{27} , thereby making the emitter of transistor J_7 more positive than before.

When, as the result of the switching off of transistor J_8 , the end of the ticket has been cut off, the rear microswitch M_1 will return to its closed position and cause the trigger output of the sensing system in the collector circuit of transistor VT_3 to bypass the network controlling the base voltage of transistor J_7 . The voltage across resistor R_{24} therefore returns to its original bias level; but since, due to the switching off of transistor J_8 , the emitter of transistor J_7 has, as mentioned above, become much more positive than the bias voltage, the transistor J_7 remains in its "on" condition. This fact prevents any unintended repeat operation of the guillotine even if pressure on the ticket is maintained so that the ticket, after the cutting-off of its original end portion, once more opens the rear microswitch M_1 , since the transistor J_7 , being already in its "on" condition, will not again be affected by

the resulting increase in current through the resistor R_{24} .

When the ticket is now withdrawn, not only rear microswitch M_1 but also front microswitch M_2 will close. The closing of the front switch M_2 reduces the base bias of transistor J_7 sufficiently to cause transistor J_7 to return to its "off" condition, thereby causing transistor J_8 to be switch on, and resetting the logic circuit.

As mentioned before, the switch-off of transistor J_8 is utilized to operate the guillotine and printing mechanism. This is effected by a relay S which is controlled by a further transistor J_9 connected as shown in FIGURE 10. The operation is as follows:

As long as transistor J_8 conducts, the voltage drop in resistor R_{29} causes the collector voltage of transistor J_8 to be considerably more positive than a voltage which is applied to the positive terminal of a diode D_9 , which latter therefore is nonconducting and the charge of a coupling capacitor C_{14} will correspondingly be low. Now base current will flow through transistor J_9 , which is a germanium transistor whose emitter circuit includes a forward-biased silicon diode D_{11} . When now, after insertion of a valid ticket, transistor J_8 becomes switched off, its collector voltage grows more negative, causing base current to flow in transistor J_9 , which thus becomes switched on, and condenser C_{14} will at the same time be charged. The resulting collector current of transistor J_9 is utilized to operate the relay S controlling the guillotine and printing mechanism. As capacitor C_{14} approaches its full charge, the charging current, which is also the base current of transistor J_9 , will rapidly be reduced, causing transistor J_9 to be switched off again after a short period, thereby releasing the ticket after minimum of time. When the ticket has been removed from the machine, causing transistor J_8 to become conducting again, the base of transistor J_9 becomes positive by the forward voltage of a shunt diode D_{10} , thus restoring the initial condition.

What I claim is:

1. Apparatus for detecting the presence on a carrier of an amount of magnetic or electroconductive deposit between a predetermined maximum and a predetermined minimum which comprises in combination: a magnetic bridge in which three magnetic cores, each having a winding, are mechanically coupled by their fluxes, means for locating such carrier with the deposit in a predetermined position relative to said cores, the cores being so arranged with reference to the deposit when the carrier is thus located, that such deposit discriminately influences the flux that couples one of the three cores with one of the other two cores, means for feeding the winding of one of the cores with alternating current to form a transformer primary winding, while the winding of a second core is utilised as a secondary winding, the winding of the third core being so connected in series with either of the two windings referred to as to oppose the field effect thereof, means for providing a residual unbalance in such manner that in the absence of a deposit there is a residual secondary-voltage output in antiphase to the variation produced by the presence of an acceptable deposit, means for feeding the magnetic bridge with current from an alternating-current source, means for rectifying the resultant

60

voltage output, means for deriving from said source a reference voltage and for rectifying said reference voltage, and a voltage comparator having a first input to which the rectified said resultant voltage is applied and a second voltage input to which the rectified said reference voltage is supplied to produce a comparator output whose polarity is determined by the algebraic sign of the difference of said rectified voltages.

2. Apparatus as claimed in claim 1, wherein the means providing a residual unbalance are so constructed that this unbalance is in antiphase to the voltage variation produced by a magnetizable deposit.

3. Apparatus as claimed in claim 1 wherein the magnetic bridge comprises three cores arranged side by side to extend parallel to each other to the same side of a common end surface at the corners of an equilateral triangle and all jointly embedded with their windings in a molding of insulating material.

4. Apparatus as claimed in claim 1, including an oscillator feeding the magnetic bridge, and means for deriving a reference voltage from the same oscillator.

5. Apparatus as claimed in claim 1, wherein the means providing a residual unbalance include a potentiometer supplied with current derived from said source, the voltage output of the potentiometer being connected in series with the said secondary winding.

6. Apparatus as claimed in claim 4, further comprising a trigger or gate circuit to which the comparator output is fed, and which is arranged to become operative to produce an acceptance response only when the biased bridge output is maller than the reference voltage and subject further to a logic circuit which has two other inputs respectively controlled by two microswitch feelers each controlled by the presence of a ticket in the device, one feeler being arranged to be operated only when a ticket is fully inserted against a stop determining the checking position, and the other being arranged at a point on the path of the ticket from an insertion opening to the stop so as to be operated whenever a ticket has been inserted beyond an intermediate point of this path.

7. Ticket checking apparatus as claimed in claim 6, wherein the logic circuit is arranged to permit an acceptance response only when both microswitches have been operated, and then to prevent a further acceptance response until at least the last-mentioned one, one of the microswitches has been closed and reopened after the preceding acceptance response.
